UNITED STATES PATENT OFFICE.

JOSEPH J. BURKE AND WILLIAM F. MCPHEE, OF JOLIET, ILLINOIS.

SMUDGING DEVICE.

1,162,975.

Specification of Letters Patent.

Patented Dec. 7, 1915.

Application filed November 18, 1914. Serial No. 872,705.

To all whom it may concern:

Be it known that we, JOSEPH J. BURKE and WILLIAM F. MCPHEE, both citizens of the United States, residing at Joliet, in the county of Will and State of Illinois, have invented certain new and useful Improvements in Smudging Devices, of which the following is a specification.

Our invention relates to an apparatus for generating an extensive smoke volume to be used in fumigation, disinfection, or which is applicable for use by hunters, trappers and the like for the purpose of "smoking-out" game from trunks of trees, burrows, and other hiding places.

The principal object of our invention is the provision of a smudging device that is easy to handle and operate; that is effective in its operation; and is light in construction so that, when carried by hunters and trappers, will not materially add to the weight of their impediments.

Other objects are to construct a smudging device that is durable in construction, inexpensive to manufacture and use, and which is well adapted to the divers uses for which it may be employed.

These and numerous other objects we prefer to accomplish by the means and in the manner hereinafter fully described and as more particularly pointed out in the claim, reference being had to the accompanying drawings, forming a part of this specification, in which:

Figure 1 is a longitudinal side elevation of our improved smudging device showing a length of hose attached to the discharge nozzle thereof. Fig. 2 is a top plan thereof with the housing of the fan or blower broken away to disclose the interior thereof. Fig. 3 is a central longitudinal section of the smoke or smudge generating chamber showing the same disengaged or detached from the apparatus and drawn to an enlarged scale. Fig. 4 is a transverse vertical section of the generating chamber taken on line 4-4 of Fig. 3.

Referring to the drawings, similar reference characters indicate the same parts throughout the various figures. In these drawings 5 represents a suitable substantially rectangular shaped plate that is provided with a longitudinal disposed extension 6, which latter, together with said plate 5, form the main or supporting frame upon which an apparatus is adapted to be mount-

ed. This frame is preferably disposed in a vertical plane with said extension projecting and forming a continuation of the longitudinal edge thereof as shown in Fig. 1 of the drawings. Secured in any suitable manner, preferably by bolts or rivets, is a cylindrical shaped housing 7 the axis of which is transverse to the frame 5 and which is provided in its ends 8 with bearings for the horizontally disposed rotatable shaft 9 of a fan or blower 10 the hub of which is rigidly secured to the said shaft and rotatable therewith. Housing 7 is also braced to said frame 5 by a substantially L-shaped bracket 11 the shorter arm of which fits snugly against the adjacent cylindrical wall thereof and has a lateral extension 12 fitted against and secured to the frame 5 while its longer arm extends across the outer end of the housing 75 to about the center of width of latter where it is provided with an outside bearing for adjacent end of shaft 9.

The opposite end of shaft 9 is extended beyond its bearings in the frame 5 and to this protruding end is pinned a gear 13, adapted to be driven by a relatively large gear 14 rotatably mounted in bearings in a circular shaped bearing frame or spider 15. This spider or bearing frame has two substantially L-shaped brackets 16 projecting radially therefrom that are bolted to the frame 5, and diametrically opposite thereto said spider has a lateral bearing lug 17 in which the extended end of shaft 9 is journaled. 85 Suitable alining bearing bosses 18 are provided on the outer face of the spider for a vertically disposed crank-shaft 19 the upper end of which extends substantially above the horizontal plane of the upper segment 95 of the housing where it is pivoted with an operating handle through the medium of which the same is driven. Intermediate its bearings crank-shaft 19 has a horizontally disposed beveled gear mounted thereon that 100 meshes with and drives a gear 20 disposed upon the adjacent side of the hub of gear.

Mounted upon the outer end of extension 105 is a suitable cylindrical-shaped generating chamber 21 the ends of which are closed by suitable heads or plates 22 and 23 that are provided at about their centers with openings 22^a and 23^a over which screens 25 are secured. Conical shaped caps or hoods 26 and 27 are telescopically fitted over the 110 ends of said chamber as shown so to constrict the inlet and discharge to or from

the chamber. Cap 27 has its tapered end open and fitted into the lower arc of the blower housing from which it is adapted to receive the blast of air, while the outer end 5 of cap 26 is provided with a suitable nozzle 28 from which the smoke or smudge is adapted to be discharged. Nozzle 28 is adapted to be inserted or secured to the end of a suitable lead of hose 29 that may be of 10 any desired length so as to reach a distance from the operator or be inserted in the hollow tree trunk or burrow for the purpose of reaching an animal hiding therein. In order to facilitate the movement of the hose 15 we prefer to mount a spider 30 on its outer end in the radial arms of which are journaled suitable rollers or pulleys 41.

When it is desired to operate the apparatus a quantity of coarsely woven fabric 42 20 such as burlap or the like is spread out and sprinkled with powdered sulfur or the like and then wound into a roll or bundle that is placed in the chamber 21 as will be observed by reference to Fig. 3 of the drawings. 25 This bundle is then ignited at the end nearest the blower and the chamber mounted on the cap 27 whereupon the crank operating the blower is slowly rotated which causes the rapid burning of the sulfur and fabric 30 and forces a large volume of smoke out of the nozzle of the cap 26 which may be readily directed in any direction desired.

While we have shown and described a specific form of our improvements it of 35 course will be obvious to others skilled in the art to which it pertains that various changes or modifications of the same are possible without materially departing from the spirit of our invention. We therefore

desire it understood that all refinements hereof are contemplated within the scope of our invention as set forth in the appended claim.

It will be further understood that the device may be constructed of divers sizes according to the class of work the particular apparatus is called upon to perform, as for example it may be built of very large dimensions and mounted upon a wheel truck for convenient handling when smudging orchards, vineyards and the like. Our smudging device is also well adapted to use in fumigating contagious disease wards of hospitals, also for exterminating vermin and rodents in residences, stables and other buildings.

What we claim as new and desire to secure by Letters Patent is:

In combination with a smudging device comprising a generating chamber provided with an outlet opening, a flexible tube leading therefrom, and means adjacent the open end of said tube for spacing the same from the wall of an opening through which the same is adapted to be inserted, said spacing means comprising a collar fitting the end of said tube, legs radiating from said collar, and rollers journaled to the extremities of said legs.

In testimony whereof we have hereunto set our names in the presence of two witnesses.

JOSEPH J. BURKE.
WILLIAM F. MCPHEE.
